SECTIONAL BOILER ASSEMBLY

Andrew J. Gallagher, St. Louis, Mo.

Application April 27, 1945, Serial No. 590,677

5 Claims. (Cl. 122—223)

1

This invention relates to improvements in sectional boiler assemblies, and more particularly to an improved and more economical construction of individual sections, and a novel and advantageous arrangement of a plurality thereof to constitute a boiler or heat exchanger.

It has long been realized as advantageous to increase the length of path or line of flow of the flame and hot combustion products adjacent the heat-absorbing portions of steam and hot water boilers, and similarly to increase the path of travel of either or both of two fluids circulated in adjacency for heat-exchange purposes generally. In the construction of boilers, (which may for present purposes be considered as one class of heat exchangers,) frequent attempts have heretofore been made in cast iron boilers and sections thereof, to provide for a back-and-forth or zig-zag course of travel of the hot gases from which heat is absorbed by water or steam circulated within the boiler or section. Such expedients require particular conformations of cast elements, and introduce expensive and complicated casting procedures, coring and patterns, and have resulted in a high cost and lack of uniformity in production, and with but an indifferent degree of success in actual usage. The present invention, accordingly, has as its principal objective, to provide lengthened paths of travel of both heating and heated fluids, particularly in a welded or fabricated boiler element or section, in distinction from cast-cored structures.

A further general and important objective of the present improvements is attained in provisions compelling a zig-zag or back-and-forth circulation internally of a boiler, or each section of a plurality thereof in a boiler, and further to compel, by the same structural provisions, a zig-zag, back-and-forth or reversely curved path of flow of flame and combustion gases externally of at least one and preferably both sides of a heat-absorbing section or unit.

Yet another and highly important objective is attained in a simplified structure involving the use of elements within a boiler or section which serve effectively the combined functions of tie or stay bolts or distance pieces, and fluid baffles internally of the section, such as to compel a substantially lengthened and evenly distributed flow of water or steam in interiorly traversing the section.

Yet another object is attained in a novel construction of boiler section and a novel assembly of several thereof, which compels a back-and-forth or zig-zag flow of fluid external of the sec-

2

tion in each of two planes mutually at right angles to each other, for example, a zig-zag flow in a plane lengthwise of the section of the boiler, and a zig-zag flow between adjacent sections of the boiler and generally in a plane transversely of the sections but externally thereto.

Still further important structural improvements are realized in an improved construction of welded plate sections, such that identical and adjacent sections in an assembly thereof may be relatively inverted to result in the lengthened or distributed fluid flow above mentioned, and such that any individual section may be removed or replaced without necessarily disturbing any other section.

A still further important object is attained in an improved welded-plate boiler section which, of itself, is or may be formed entirely of planar elements without shaping other than cutting to fixed and easily predetermined dimensions, and without elaborate special tooling or equipment; an improved header construction in a multiple section boiler, and an improved and more permanent arrangement for mounting and supporting external insulation in adjacency to heated boiler surfaces.

The foregoing and numerous other objects will more clearly appear from the following detailed description of a preferred embodiment of the invention, particularly when considered in connection with the accompanying drawing, in which:

Fig. 1 is a vertical, transverse sectional elevation in which certain of the elements are broken away for clearness, other parts shown in section to reveal internal construction, and other accessory elements shown in elevation for completeness;

Fig. 2 is a fragmentary vertical sectional view as taken along line 2—2 of Fig. 1; and

Fig. 3 is an isometric view of a single section showing a preferred arrangement of baffle plates externally thereof.

Referring now by characters of reference to the drawing, although the structure is applicable to steam boilers or for hot water circulating systems, and may be manufactured in a variety of sizes and capacities, the single illustrative example selected shows a steam boiler in which a relative high water level is maintained, and in which the elements of the boiler and sections are fabricated substantially throughout of sheet materials such as boiler plate and the like, cut as by suitable templates, and welded by usual flame or arc welding equipment not necessarily here to be de-

tailed, these processes per se being well known in the art.

Briefly to describe for completeness, the assembly as a whole, this includes a hollow base structure generally indicated at 10 which may be supported as by a concrete base or floor, or otherwise as desired, and which in turn serves as the primary support for a plurality of sections 11 hereinafter described in more detail. The base 10 is preferably a fluid containing base, the spaces within which are in communication with the sections, suitable connections being indicated at 12 and 13. In the example shown, containing five sections which are or may be all of identical construction, the sections are cross-connected through a lower header generally indicated at 14 and an upper header generally indicated at 15. Mounted above and suitably supported either on or independently of the assembly of sections, is a steam drum 16, between the header 15 and the drum being interposed a riser pipe 17, a downflow pipe or conduit 20 serving to interconnect the lower portion of drum 16 and the lower header 14. Still a further connection 21 is preferably employed from the upper portion of the drum 16, thence extending downwardly to an adjacent connection 13 (Fig. 1). Such connection, communicating with adjacent section 11, also establishes communication between line 21 and header 14. In the line 21 is advantageously disposed a water gauge 22 with a sight glass 23 and try-cocks 24.

There has been omitted from the drawing any showing of burners, grates, or other structure indicating applicability to any specific fuel, since the boiler is adapted for gas firing, use with an oil burner or may be provided with grates for solid fuel combustion if desired, the selection of fuel being a matter of choice. Similarly, such elements as outside enclosing portions have been at least in part omitted, since apart from certain fastening and insulation advantages later to be described, the type of boiler enclosure may be a matter of choice.

Referring first briefly to the base 10, this includes a plurality of vertical wall elements 25 and 26, a rear wall structure 27 and, as illustrated, a pair of horizontal, depthwise extending I-bar supports 30. Welded into permanent assembly in certain of the compartments of the base, are a plurality of horizontal baffle plates 31 which are suitably spaced from each other, and optionally disposed in vertical rows in which the corresponding plates are somewhat staggered after the manner of the baffle plates of the sections 11 later to be described. It will be seen that the spaced walls 25-26 of the base terminate upwardly in supporting plates 32, forming flat planar surfaces for the support of the sections 11 which may bear directly thereon as shown.

Proceeding now to a description of the sections and their assembly, each thereof is preferably of a narrow, rectangular, box-like form constituting a fluid-tight enclosure, and is normally disposed vertically in assembly with adjacent sections in spaced relation as hereinafter described, so as to provide a substantial space for travel of flame and hot gases between adjacent sections. Each of the sections consists of a pair of opposite, parallel, similar, planar side plates 33 and 34. These may conveniently be formed of boiler plate, for example, but without restriction, of $\frac{1}{4}$ " - $\frac{3}{8}$ " gauge which may also be employed for others of the planar elements of the fabricated

structures. A narrow planar top piece 35, and a similar bottom element 36, together with similar end plates 37 and 38 are all welded together in fluid tight relation along the lines or zones of their juncture, thus serving to complete the enclosure of the chamber within the section. In at least one of the end plates 37 and 38, are provided two ports, one near the upper and the other near the lower end of the section, the ports being of a somewhat flattened form. These are shown at 40 near the top, and 41 near the bottom of end plate 37 of the section. These ports serve, as will appear, for communication with the headers 14 and 15.

Both headers 14 and 15, since they are or may be similar in construction, may adequately be described by reference to the upper header 15 which, as will appear from Figs. 1 and 2, is built up of a plurality of special I fittings 42. Each such fitting includes a through-passage-forming portion of substantial diameter provided at its ends with flanges 43 suitably apertured for the reception of securement bolts 44, there being, as may be desired, a suitable gasket or packing material (not shown) between adjacent flanges. A branch-passage-forming portion 45 extends at substantially a right angle but somewhat downwardly below or upwardly from the axis of the major portion of the fitting. As will best appear from Fig. 2, the branches 45 are welded as at 46, to the adjacent end wall 37 of the immediately connected section, and about the adjacent port 40 or 41. It will now have been observed that the length of each through-portion of the header fittings, corresponds substantially to the overall width of each section 11, including its baffle portions later to be described in more detail. Thus when the sections are in place and uniformly spaced, and the flanges 43 bolted up, the center spacing of the I fittings will conform substantially to the spacing of vertical median planes of the several sections.

Proceeding now to a description of the construction and arrangement of the baffle plates, 45 in each of, and as extended between the several sections in an assembly of a plurality thereof, it is a preference prior to welding up the elements of each section 11 to provide in each of the side walls or plates 33 and 34 a series of rectangular apertures conforming fairly closely in area to the cross sectional area of one of the baffles or baffle plate elements 50. The locations of certain of the rectangular apertures are indicated at 51 (Fig. 3), and are arranged in corresponding number and in registration, in the opposite side walls. At least of a length to bridge the side plates of each section, and preferably extending an appreciable distance laterally of each side plate, hence of each section, each of the several baffle plates 50 includes an internal stay, bridging and baffle portion which lies cross-wise of the section and serves structurally to tie together its side walls, preventing bulging, spreading, warping and either convergence or divergence. Each of the plates is by preference of an overall length, hence of a horizontal extent, at least equal to twice the thickness or internal cross dimension of the section, so that there projects laterally of each side face of the section a substantial length of the baffle plate. These extensions or extended plates, as will now appear, serve the dual purposes of augmenting heat-absorbing surface and constituting a baffling arrangement for the flame and hot gas proceeding in a generally upwardly direction between

the sections. In the drawing, these externally protruding, horizontal plate-like portions lie preferably at substantially a right angle to the adjacent section wall, and are indicated at 52. It will now have appeared as a preference in fabricating each of the sections, and assuming the opposite side walls to have been suitably apertured, first to dispose the baffles or bridge plates through the opposite apertures of the side walls, then in the course of welding up each section, to complete the assembly of the baffles by external welding in the zones 53.

The arrangement of baffles as shown in the sections and assembly is particularly advantageous for reasons which will be discussed. It will be noted, as from Figs. 2 and 3, that the baffles are arranged in vertical rows in each section, those of each row being evenly vertically spaced, but spaced differently in respect to top and bottom of the section, with the result that corresponding baffles of adjacent vertical rows are relatively staggered. It will further be noted that in each section the baffles of each row extend horizontally over to those of the adjacent row, thus compelling a distinct back-and-forth or zig-zag pattern of generally upward fluid flow, say of water, as the heated fluid moves from bottom to top of the section in the course of heating. Obviously the same pattern of baffle arrangement prevails externally as internally of any given section.

It will now have appeared from the arrangement of baffles described, and since the headers 14 and 15 are evenly vertically spaced from a horizontal median through each section, that adjacent sections may be relatively inverted, as is done in assembly, with the result of staggering the baffles of the rows which lie in adjacency in the assembly. This arrangement best appears from Fig. 1. In Fig. 1, in which the assembly is viewed endwise of the sections, it will appear that the staggered arrangement of baffles in corresponding and adjacent vertical rows of adjacent sections, is such that the flow of hot gases from bottom to top of the intersectional spaces is given a distinctly zig-zag trend in a vertical plane transverse of the several sections. It will now have appeared from the earlier description of the baffles on each individual section, that to the extent the gases tend to traverse the intersectional spaces in a direction from end to end of the sections, there will be imparted thereto a similar zig-zag flow. Since the same arrangement of baffles prevails internally of each section, it will now have appeared that the same zig-zag trend of flow is imparted to the water or other fluid internally of each section, all with obvious effect in augmenting length of flow of both fluids, and of effectively increasing heat-absorbing or heat-transferring area and effectiveness.

There has been omitted from the present drawing, in zones above the sections and upper header, any illustration of conduits for flue gases and flue connections. These are or may be conventional, and of themselves form no part of the present improvements.

The manner of erecting and assembling the various components of the boiler is believed to have appeared fully from the description of its parts, it being noted that suitable fastening means consisting of hook bolts, and other expedients of this type may be employed where desired. Similarly, it is felt that no further description is necessary in addition to that given in

connection with description of parts and reason for design, to illustrate the operation.

It is usually desirable that the boiler assembly be provided with suitable external closure or finishing members. These may conveniently be in the form of planar or substantially planar side and end sheet metal elements as indicated for example, by two such elements 54 and 55.

A further improvement results from the provision of the externally projecting portions 52 of the baffles 50, in that these serve greatly to facilitate the application of external insulation materials to the sides, back and other surfaces of a boiler or section. It will appear, for example from Fig. 1, that the portions 52 on the outside of each of the end sections of the assembly present a series of spaced superposed shelves each at a right angle to the vertical surface of the section. The application of pulped or bulk insulation to external boiler surfaces, has long been a source of difficulty. Such materials as magnesium or asbestos insulation is commonly applied as a pulped mix, having setting properties and some adhesion to adjacent metal surfaces. Nevertheless such materials ordinarily require reinforcement of various wire, wire mesh or other types in order to retain them dependably in place. All such makeshift anchoring expedients are obviated by the present improvements. The relatively closely spaced protruding plates 52 constitute for this purpose, and as will readily appear from the drawings, a vertically spaced series of cell-like spaces between the baffles or shelves 52. This arrangement serves admirably of itself, to retain insulation introduced to these spaces, and only slightly compressed or packed therein. As a means of assuring retention of the insulation in place, some of the protruding baffle ends 52 are provided with a horizontal aperture 57 which serves to receive the threaded end of a fastening screw 58 which projects through suitable apertures (not shown) in each of several locations in the outside closure plates 54 and 55. It is suggested that, say at each side of the boiler, five such zones of securing be provided, one each in each upper and lower corner region, and one substantially centrally located in the cover or closure 54 or 55.

In applying and retaining the pulp insulation material by this expedient, each of the spaces between the several superposed baffles is filled with the pulp material, care being taken to clear the screw apertures of any pulp, following which the closures are applied with screws 58 in place, and the screws threaded up.

It will have appeared that the various features of present structural improvement serve fully to attain each and all of the objects hereinabove specifically stated, and numerous others referred to and implied from the description. Although the invention has been described, for completeness, by making detailed reference to a presently preferred embodiment, the detail of description is to be understood solely as illustrative, and not as limiting the possibilities of the invention, numerous variants being possible within the scope and spirit of the claims hereunto appended.

I claim as my invention:

1. In a boiler assembly, a plurality of heat-absorbing sections each of box-like construction, and characterized by opposite substantially vertical and planar side walls, a plurality of external baffle plates carried by each of the sections, and arranged substantially normal to the adjacent side wall thereof, the adjacent sections being lat-

erally spaced from each other to provide a space for flame and gas travel therebetween, the external baffles on a given side of each section being arranged in vertical rows, those of each row being evenly vertically spaced and staggered in height, in the section, relative to adjacent vertical rows of the baffles, the group of baffles of each vertical row being dissimilarly spaced from top and bottom of the section whereby to enable, upon inversion of the section, a different baffle location in assembly, whereby the path of travel of flame and gases in traversing intersectional spaces, is compelled to assume a zig-zag course; the assembly including upper and lower headers each having a connection with one of the sections at a constant distance from a horizontal median through the section, whereby to enable relative inversion of the sections with constant location of header connections.

2. The combination and arrangement of elements as set forth by claim 1, but further characterized in that the plates are arranged on the side of each section in a plurality of vertical rows, and in such manner that the baffle plates in adjacent rows on a given side of each section are relatively staggered, and such that those plates of any vertical row are similarly staggered with respect to the confronting row of plates on the adjacent section.

3. In a sectional boiler, a plurality of sections each including a box-like body characterized by substantially planar side wall elements and each section including a plurality of planar baffle plates, each extending through and laterally beyond each side of the section, the baffle plates being arranged in vertical rows in each section with adjacent such rows staggered in such manner that adjacent sections may be relatively inverted, and so present a corresponding arrangement of baffles in adjacent sections, but in vertically spaced relation, whereby to provide a zig-zag flame path of substantial width extending between and substantially co-extensive with the lateral surfaces of each pair of adjacent sections from bottom to top of the assembled boiler, and a pair of header elements external to each section, and providing separable connections enabling introduction and removal of each section, separately from other sections.

4. The combination and arrangement of ele-

ments as recited by claim 3, but further characterized in that the baffle plates are arranged in both vertical rows and horizontal rows, each baffle plate extending through and laterally beyond each planar side of the section, with the baffle plates in relatively staggered vertical rows internally of the section, and in relatively staggered, vertical rows externally of the section.

5. A sectional boiler assembly including a plurality of individually removable box-like sheet metal sections, each of narrow rectangular form, each provided with internal and external baffles bridging and extending laterally beyond the side walls of the sections, and a pair of headers, each header being common to the assembly of sections constituting the boiler, each header being constructed of a linear series of T-fittings, the through passages of which are provided with bolted flanges, and each fitting including a branch passage welded to an apertured portion of the end wall of the section, the length of each T-fitting approximating the over-all depth of the section including external baffles, and the arrangement of fittings being such that upon removal of the bolted connections to and from each such fitting, the individual section and connected portion of the header may be removed from and introduced to the assembly as a unit without disturbing any other section of the assembly.
